(57) **CLAIM**

The ornamental design for a grill bag, as shown and
described.

DESCRIPTION

FIG. 1 is a top perspective view of a grill bag in the closed
configuration showing my new design;

FIG. 2 is a top plan view thereof;

FIG. 3 is a bottom plan view thereof;

FIG. 4 is a front elevational view thereof;

FIG. 5 is a right side elevational view thereof, the left side
elevational view being a mirror image thereof; and

FIG. 6 is a rear elevational view thereof.

FIG. 7 is a top perspective view of a grill bag in the open
configuration showing my new design;

FIG. 8 is a top plan view thereof;

FIG. 9 is a bottom plan view thereof;

FIG. 10 is a front elevational view thereof;

FIG. 11 is a right side elevational view thereof, the left side
elevational view being a mirror image thereof; and,

FIG. 12 is a rear elevational view thereof.

The broken lines in FIGS. 1 to 12 showing fasteners for
securing the grill bag in the closed configuration form no
part of the claimed design. The break lines and brackets in
each of FIGS. 1-12 indicate indeterminate length and width
of the grilling bag, and the appearance of any portion of the
grilling bag between the break lines forms no part of the
claimed design.
